UNITED STATES PATENT OFFICE

LILLY COOPER HEATON, OF PENDLETON, ENGLAND.

ENVELOP OR BAG FOR HOLDING GARMENTS.

Specification of Letters Patent. Patented July 25, 1916.

1,192,422.

Application filed May 17, 1915. Serial No. 28,780.

To all whom it may concern:

Be it known that I, LILLY COOPER HEATON, a subject of the King of Great Britain, residing at Pendleton, in the county of Lancaster, England, have invented certain new and useful Improvements in Envelops or Bags for Holding Garments; and I do hereby declare the following to be a full, clear, and exact description of the invention, such as will enable others skilled in the art to which it appertains to make and use the same.

My invention relates to improvements in suspensible garment envelopes or bags such as are made of paper, fabric or the like, one side of which is composed of flaps adapted to fold onto each other and the object of my invention is to provide an improved construction of such envelop or bag which renders the same thoroughly dust-proof.

To this end my invention consists in so forming the top portion of such envelop or bag as to form a pocket, and providing the part below the said pocket at each side edge with a flap adapted to fold onto each other, the bottom edge with a flap to fold onto the said side flaps and the said pocket with a flap to hold onto the said bottom flap and side flaps and completely cover the latter. The said envelop or bag is provided with fastenings adapted to secure the said flaps together. I attain this object by the means illustrated in the accompanying drawing, which illustrates one embodiment of my invention—

Figure 1 being a front view, Fig. 2 a cross section, and Fig. 3 a longitudinal section of the envelop or bag closed, and Figs. 4 and 5 are front views respectively of the envelop or bag partly and completely opened.

Similar letters refer to similar parts throughout the several views.

Referring to the drawing, the top edge *b* of the envelop or bag is closed and also each side edge *a* extending therefrom for a suitable distance, to form a pocket *a'*, see Figs. 1, 3, 4 and 5. By preference I form these edges with plaits *a''*, see more particularly Figs. 2 and 3. On each side edge or plait *b* below the said pocket I form a flap *c*, see Fig. 5, adapted to fold upon each other as shown in Fig. 4, while on the bottom edge *d* I form a flap *e* adapted to fold upon the flaps *c*, and on the said pocket a flap *f* adapted to fold upon the flaps *c* and *e* and completely cover the side flaps *c*, as shown in

Fig. 1, and be secured to the flap *c* by means of suitable fastenings, say such as an elastic loop *g* on the flap *e* adapted to be placed on a button *h* on the flap *f*. At the open end *ee* of the pocket *a'* the sides are slightly slit to allow of placing the upper ends of the flaps *c*, *c* into the pocket *a'* and thereby render the envelop or bag dust-proof.

In the present instance the means for suspending the envelop or bag consist of a rail *h* placed loosely inside the envelop or bag and furnished with a hook *i* passing through an aperture in the top edge of the bag. The said aperture may however be dispensed with and the hanger secured to the outside of the envelop or bag. The garment is enclosed in the envelop or bag by first opening out all the said flaps, as shown in Fig. 5, then placing the garment upon the envelop or bag and pushing the part of the garment opposite the pocket *a'* into the same, then folding the side flaps *c*, *c* upon one another with upper ends placed into the said pocket, as shown in Fig. 4, then the bottom flap *e* *ee* upon the said side flaps, the top flap *f* upon the said side flaps and the bottom flap, and finally placing the loop *g* onto the button *h*. In large sizes of envelops or bags I may furnish also each side edge with suitable fastenings, say consisting of elastic loops *g* secured to the back and buttons *h* secured to the front, as shown in Fig. 1.

The envelop or bag described may be made of various sizes and be also utilized as an advertising medium.

I claim:

1. A suspensible garment envelop or bag comprising a pocket at the top, flaps below the said pocket extending from each side *ee* edge of the envelop or bag adapted to fold upon each other, a flap extending from the bottom edge of the envelop or bag adapted to fold upon the said side flaps and a flap extending from the open end of the said pocket *ee* adapted to fold upon the said side and bottom edge flaps and completely cover the said side edge flaps.

2. A suspensible garment envelop or bag comprising a pocket at the top, a plait along the top edge and the side edges of the envelop or bag, flaps below the said pocket extending from the plaits at each side edge of the envelop or bag adapted to fold upon each other, a flap extending from the bottom edge *ee* of the envelop or bag adapted to fold upon the said side flaps and a flap extending from

the open end of the said pocket adapted to fold upon the said side and bottom edge flaps, and completely cover the said side edge flaps.

5 3. A suspensible garment envelop or bag comprising a pocket at the top, flaps below the said pocket extending from each side edge of the envelop or bag adapted to fold upon each other, a flap extending from the bottom edge of the envelop or bag adapted to fold upon the said side flaps, a flap extending from the open end of the said pocket adapted to fold upon the said side and bottom edge flaps and completely cover the said side edge flaps, and means at each side and bottom edge for securing the flap extending from the open end of the said pocket to the envelop or bag.

4. A suspensible garment envelop or bag comprising a pocket at the top, a hanger in the said pocket, flaps below the said pocket extending from each side edge of the envelop or bag adapted to fold upon each other, a flap extending from the bottom edge of the envelop or bag adapted to fold upon the said side flaps and a flap extending from the open end of the said pocket adapted to fold upon the said side and bottom edge flaps and completely cover the said side edge flaps.

Signed at Manchester, England, this 4th day of May, 1915.

LILLY COOPER HEATON.
